COMBINED FERRULE AND FOOT FOR FURNITURE

Bruce R. Ogden, Marrickville, near Sydney, New South Wales, Australia, assignor to Claude R. Ogden & Co. Pty. Limited, Marrickville, near Sydney, New South Wales, Australia, a company of New South Wales, Australia

Filed Aug. 20, 1962, Ser. No. 71,376

Claims priority, application Australia Feb. 20, 1962

Term of patent 14 years

(Cl. D33—1)

FIG. 1

FIG. 2

FIG. 3

FIG. 4

FIG. 1 is a perspective view of the combined ferrule and foot for furniture as seen from the top,

FIG. 2 is a perspective view thereof as seen from the bottom,

FIG. 3 is side view of the ferrule and foot,

FIG. 4 is a plan view from the top of FIG. 3.

The design is characterized by a ferrule being of square cross-section having inwardly tapering sides in combination with the specifically configured foot member, all as shown.

I claim:

The ornamental design for a combined ferrule and foot for furniture, as shown and described.
